DEAERATION APPARATUS

John R. McDermet, Hempfield Township, Westmoreland County, Pa., assignor to Elliott Company, Pittsburgh, Pa., a corporation of Pennsylvania

Application September 14, 1939, Serial No. 294,910

17 Claims. (Cl. 261—115)

This invention pertains to heating and deaerating or degasifying of liquids, and more particularly, to procedure and apparatus for purifying feed water.

The present invention has particular application to procedure and apparatus for deaeration where the apparatus is subjected to swaying and tilting, for example, to conditions such as encountered in marine work.

As will be appreciated, the ordinary form of deaerator becomes rather inefficient and ineffective when employed under conditions such as encountered in marine use. The apparatus should be capable of effectively operating even although subjected to constant tilting, tipping, or swaying action. Heretofore, the so-called marine types of deaerators have been rather inefficient from an economy standpoint. That is, in one construction, it was found necessary to atomize the feed water in order to obtain suitable deaeration; atomization was necessary to minimize so-called water hammer and other pounding actions adjacent the spray apparatus that are due, in part at least, to the action of steam upon the water being deaerated. Such a type of deaerator, in addition to utilizing or wasting enormous amounts of energy (particularly steam velocity energy) tends to increase the wear and corrosive action upon the inside portions of the apparatus involved.

In view of the above considerations, it has been an object of my invention to provide new and improved procedure and apparatus for effectively deaerating feed water under unfavorable conditions, such as encountered in marine operation.

Another object of my invention has been to develop an improved procedure and apparatus employing, in general, efficient operating characteristics of a counter-flow induction type of heater such as set forth in my Patent No. 1,742,998, entitled "Method and apparatus for treating liquids," showing an apparatus suitable for a relatively stationary installation.

A further object of my invention has been to provide an efficient and practical form of deaerating apparatus that will be operative over a wide range of load variations.

A still further object has been to devise a system for liquid deaeration that will eliminate the disadvantageous features heretofore inherent in apparatus of the marine type and that will have an economy and effectiveness of action.

These and many other objects of my invention will be apparent to those skilled in the art from the drawings, the description, and the appending claims.

In the drawings:

Figure 1 is a vertical view in elevation showing a section through a deaerator unit constructed in accordance with the principles of my invention;

5 Figure 2 is an enlarged detailed view in elevation of a valve mechanism taken along the line II—II of Figure 3;

Figure 3 is an enlarged top plan view taken along line III—III of Figure 1;

Figure 4 is an enlarged vertical sectional view taken on the line IV—IV of Figure 3; and

Figure 5 is a top fragmental section detail taken through deflecting vanes 21 of Figure 1.

In the embodiment of my invention shown for 10 the purpose of illustration, 10 represents a unit having an upper, preliminary, induction heating, and partially deaerating chamber 11, and a lower or final, thoroughfare heating, and deaeration stage or chamber 12. The bottom portion of 15 the chamber 12 has a storage space for the purified water 13, which is removed through an outlet 14. I have also shown a skimmer type of overflow 15 that does not constitute a part of the present invention; a baffle 15a is positioned to prevent the purified water from falling into the opening 15.

Feed water to be deaerated enters inlet conduit 16 adjacent the top of the apparatus and passes through the tubes of a conventional type of 20 vented-condenser 17, leaving the condenser and entering the upper deaeration chamber 11 through a conduit 18. The water, before actually entering chamber 11, passes through spray nozzle unit 20 that directs the water outwardly in a 25 plurality of vortex-like stream flows (thin vertical sheets) from the unit or substantial center of the chamber. In this manner the water is broken up into spray paths and moves about the upper portions of the chamber in somewhat, circular or rotating paths within the confines of the wall portions thereof. A suitable type of spray apparatus has been fully described in my 30 Patent No. 2,012,454, entitled "Spray device." It will be apparent to those skilled in the art that any suitable form of spray device for throwing water outwardly and about the upper portion of the chamber 11 may be employed. Deflecting 35 vents 21 are attached at a tangent to the shell 10 and extend inwardly from peripheral portions of chamber 11 in the path of the spray from unit 12 to aid in breaking up the flow and in diverting it inwardly back into steam space 11.

40 The water thus sprayed is collected by a substantially centrally-positioned and upwardly and outwardly-extending cup-shaped baffle plate 26. 45

Additional baffle means 27 extends peripherally inwardly from and about chamber 11 and above the baffle portion 26 in such a manner that the broken-up or sprayed portions of water falling from the upper portion of chamber 11 will be prevented from dropping through the space 28 between outer edges of the cup-shaped collecting baffle 26 and inner wall portions of chamber 11.

The water thus collected or received moves along the inclined surface of the cup-shaped baffle 26 to a substantially centrally-located vertical-annulus-shaped shell element 29 that projects vertically downwardly from chamber 11 into the lower chamber 12.

Steam is introduced into the unit 10 through an inlet 35 which enters laterally through and extends along the upper chamber 11, converges along its length, and terminates in a substantially vertically-depending portion 36. The portion 36 extends substantially concentrically within and in a spaced relationship with respect to the sleeve-like annulus element 29, thus providing a flow path for the partially heated and deaerated water entering the lower chamber 12 from the upper chamber 11. Steam entering through conduit 35, flows downwardly into the hollow interior or chamber of a distribution valve 40.

The distribution valve 40 has an outwardly-extending and upwardly-curved substantially symmetrically-shaped guide member 41 that may be formed or cast in two parts and secured together by suitable means, such as bolts 49a; entering water is directed downwardly along such guide from the annulus 29. A lower member or movable valve element 42 is removably and adjustably mounted on a vertically-extending support shaft 43 by means of a lock nut construction 44. As shown particularly in Figures 2, 3, and 4, the movable valve plate 42 may comprise a two-part casting suitably secured together by bolt means 49; it has annularly extending and substantially spherically-shaped valve seats 45 that contact under portions of the guide 41 at positions adjacent outer-edge portions of the elements 41 and 42; the seats 45 are spaced inwardly a short distance therefrom to provide a peripherally-extending orifice or annulus-like chamber portion 46.

The movable valve element 42 is preferably damped; for this purpose, I have shown a removable extension to the shaft 43 that is provided with outwardly-extending fin-like damper portions 50 that are adapted to project into the liquid space 13 of the lower chamber 12. The shaft 43 and the movable portion 42 are resiliently and somewhat loosely-positioned with respect to the guide portion 41 by means of a vertically-extending spring 47 that is removably connected by a shaft 48 and by removable bolt means 48a to extend from an inner portion of the conduit 35. It will be noted that the substantially complementary shape relation between guide 41 and movable (spring-loaded) valve head 42 is such that they are held in a desired relationship, although substantially loosely-positioned. Cleaning doors 25 and 25' are respectively provided for the upper and lower chambers 11 and 12.

The vent condenser 17 has, as shown, a large opening 22 through which the steam and non-condensable gases enter, and a vent opening 19 for exhausting the non-condensable gases. Condensate from the condenser 17 returns to the upper chamber 11 of the heater through a liquid-sealed overflow pipe 24. As a result, the return-

ing condensate, being in the up-flow path to the condenser inlet 22, is subjected to preliminary heating and deaeration before it enters chamber 11.

In the operation, it is believed that I have developed a number of new and improved features. As previously pointed out, the incoming feed water to be deaerated, is first subjected to a preliminary heating treatment in vent condenser 17 and then enters chamber 11 to be sprayed outwardly and about substantially the full area thereof, in order to receive heat from the steam entering from the lower chamber or compartment 12 through space or opening 28, and thus, to become heated and partially deaerated thereby. The location of steam inlet 35 is such that heat normally lost by conduction from conduit 35 is imparted to the water in the upper chamber 11 to further increase and improve the heating and deaerating action therein. The steam entering from the lower chamber, by reasons of pressure differentials existing between the upper and lower chambers, thus moves counter to the downward flow of water in chamber 11, imparting heat to the water and condensing a portion of such steam. The uncondensed portions of steam and the non-condensable gases enter condenser 17, as previously explained, through a large inlet 22. The condensed steam portions again enter chamber 11 through liquid-sealed inlet 24.

The thus-effectively heated and very thoroughly partially deaerated water falls downwardly along the passage provided between steam conduit 36 and the annulus-like shell 29. There is little frictional loss and thus the water attains a velocity that substantially corresponds to the velocity of the fall that it would attain by falling through the same vertical distance in free space. The outwardly and concavely curved guide 41 utilizes such gravity acceleration of the water to direct it in a smooth and substantially uninterrupted path radially outwardly from the center of the lower chamber 12 in a continuous sheet-like stream during conditions of normal or heavy load. Steam issues from the chamber of valve 40 in proportion to demand requirements, that is, depending upon the amount of water and deaeration to be accomplished. The steam moves past valve seat 45, at which time it has some velocity and a relatively thin thickness, to the orifice portion or opening 46 where it has little velocity and a greater thickness. It will be noted that the water and steam are directed in substantially parallel paths, and that they will thus contact somewhere, during normal load conditions, in the space beyond the valve member and the wall portions of the chamber 12. That is, the water has an upward and radial component by reason of the shape of guide 41, and thus, due in part, at least, to its greater density and lesser velocity, tends to fall in space upon the steam curtain that, as previously explained, emerges at moderate velocity from the annulus chamber 46. The water thereafter assumes a droplet, slug, or random form and its deaeration is thereby completed. At the time of contact, the water and steam are at substantially the same temperature due to the high effectiveness of the heating action in the chamber 11 and also is, to some extent, due to the fact that water flows downwardly through a space that surrounds the steam inlet conduit 36. Conduction, radiation, and convection of heat from the steam thus further heat the water in its fall and later projection.

It will be appreciated that due to the control of the direction and flow of the water and steam, the low velocity of steam flow, and the fact that the steam and water meet in a substantially parallel relationship, etc., I have obtained a new high efficiency of deaerating action without the heretofore inherent problems and difficulties involved in the atomization of the water by the deaerating steam. By providing inlet and outlet temperatures that do not vary, the water and steam are maintained in substantially constant ratio; the steam is supplied in automatically varying quantities, depending upon or in proportion to variations in the load and/or in the water introduced. By directing a water curtain and a steam curtain in substantially-parallel but eventually-converging paths, a high velocity-flow of steam is unnecessary and water-reaction pounding and vibration have been eliminated.

It will be appreciated that water is inelastic and is difficult to accelerate to high velocity due to inertia reaction corresponding to the amount of energy added thereto by the steam. This produces a rattling noise and necessitates atomization in the prior art constructions to avoid heavy bumps in the valve mechanism. The present apparatus, at high load conditions, where quantities and reactions are important, obtains a low velocity contact in such a manner that the reaction is at a minimum and is, in effect, space-insulated from the operating parts of the unit; the water and steam are intimately mixed and the former is scattered in droplet-form throughout the space 12. The structure is effectively practical in the operation under heavy, as well as normal and low loads. There is no so-called injector action in the valve device, in that in the lower chamber 12, no condensation occurs at the point of mixture. The energy for a steam curtain is suitably provided by less than one pound of steam expansion through the valve seat 45; from an energy standpoint, such a low pressure is of little consequence, and thus, must be utilized with high effectiveness.

As previously pointed out, the curved shape of the guide member 41 deflects the water outwardly and upwardly in order to utilize its velocity due to gravity acceleration in passing along the annulus 29. As no reversal of direction such as employed in atomization is required, the energy requirements are insignificant and the steam energy is utilized for water dissipation as effectively as possible without objectionable reaction effects upon the mechanical portions of the construction. The water, in passing outwardly, increasingly diffuses, and on contacting the steam, there is water dissipation due to its method of distribution prior to contact. Thus the energy requirements for spraying are additionally reduced.

It will be noted that the outer extremities of the guide portion 41 of the valve are slightly shorter than the outer edge extremities of movable or spring-loaded portion 42. This, in combination with orifices 46, is significant in obtaining an effective and efficient operation of a device under low load conditions. At a very low load, say less than 5%, there may not be enough water to form the curved water curtain nor enough steam to form the steam curtain. Water then descends through the annulus 29 and forms a pool in the concavity of guide disk 41 and over the opening to the orifice 46. When the cavity is full, the water flows over into the annulus space 46 at one or more points of the periphery and

the steam admitted in accordance with the demands merely bubbles through the water in the orifice 46 to obtain what may be termed a scrubbing action. Thus, during low load conditions, the water merely bubbles over the edge of the inner valve disk 41 and falls over the edge of the outer valve disk 42. As the load increases, the steam thickness and velocity will become sufficient to hurl the water out of the orifice in slugs or droplets. Of course, at the same time, the quantity of the water will increase and thus there is more energy of outward flow. In the transition stage from the low to normal load conditions, a portion of the water may be prevented from entering orifice 46 by an upward movement of the steam. As previously pointed out, the steam entering the chamber of valve 40, emerges past valve seats 45 with a moderate velocity and immediately expands into the annular space 46 and emerges therefrom with a lesser velocity and a greater thickness.

The above operation thus provides a highly efficient action regardless of the load conditions. It will also be noted that the major portion of the steam rising from the lower or final deaeration chamber 12 moves upwardly from space 28 between baffles 26-27. Thus, the steam can be effectively employed to preheat the water flowing downwardly along the vertical annulus 29 through the walls thereof by conduction, without interfering with the gravity acceleration of such water flow as would be the case if the steam flowed upwardly along the inside of the annulus 29. The partially contaminated steam is prevented from contaminating the water in the lower or deaeration stage.

In Figure 1, for the purpose of showing and clearly disclosing the operation of the device under normal load conditions, I have indicated water flow by solid arrowed lines and steam flow by dotted arrowed lines.

I preferably provide the steam with enough velocity as it leaves the valve that it will carry past points where it might enter the space 29-38; however, the shape and arrangement of the valve and associated parts are also such that the counterflow will be through the space 28.

Although for the purpose of illustrating my invention I have shown an illustrative form thereof, it will be apparent to those skilled in the art that many other suitable arrangements, modifications, additions, substitutions, and subtractions may be made without departing from the spirit and scope of my invention, as indicated by the appended claims.

I claim:

1. Apparatus for heating and deaerating water comprising an upper chamber for heating and partially deaerating contaminated water, and a lower chamber for completing the heating and deaeration, means for introducing contaminated water to be deaerated into said upper chamber, means positioned about said upper chamber for directing the sprayed sheets backwardly towards said first-mentioned means, means for introducing deaerating steam into said lower chamber, means for collecting water that is partially heated and deaerated in said upper chamber and for directing it downwardly under gravity acceleration into said lower chamber, said water-directing means being associated with said steam-introducing means, and resiliently mounted valve means for directing the water and steam entering said lower chamber in substantially parallel-radially-outwardly-projecting circular sheets un-

der normal and high load conditions and for causing the steam to bubble through and scrub the entering water under low load conditions.

2. Apparatus as defined in claim 1, wherein said valve means is constructed and arranged to direct the steam and water entering said lower chamber in such a manner as to minimize reactive forces upon said valve means, and to eliminate water hammer, and other objectional vibratory effects.

3. Apparatus as defined in claim 1, comprising means extending downwardly from said valve means into deaerated water being collected in such a manner as to dampen the action of said valve means.

4. Apparatus for heating and deaerating water comprising a chamber for heating and partially deaerating contaminated water, a second chamber for completing the heating and deaeration, means for introducing contaminated water to be deaerated in broken-up form within the spacing of said first chamber, means for introducing deaerating steam into said second chamber, means for directing partially heated and deaerated water from said first chamber downwardly under gravity acceleration into said second chamber, mixer means operably associated with said steam-introducing means and with said water-directing means, said mixer means having a pair of operably associated annulus-like portions, one of said annulus-like portions being shaped to direct the gravity accelerated water outwardly and upwardly within said second chamber, the other of said portions being shaped to direct the steam being introduced upwardly and outwardly within said second chamber and into a heating and deaerating relationship with respect to the upwardly and outwardly projecting water.

5. Apparatus for deaerating water comprising a chamber for heating and partially deaerating water and a second chamber for completing the heating and deaeration, means for introducing contaminated water to be deaerated into said first chamber, means for introducing deaerating steam into said second chamber, means connecting said first and second chambers for introducing partially contaminated steam from said second chamber into said first chamber to effect a preliminary heating and deaeration of the water being introduced into said first chamber, means for directing the water from said first chamber into said second chamber, mixer means operably associated with said steam-introducing means and said water-directing means, said mixer means having a member for collecting the water introduced into said second chamber by said directing means, said mixer means having a second member operably associated with said first member and providing a steam space therewith for directing the steam upwardly and outwardly within such second chamber, said first member having a portion shaped to direct the water thereover and into the steam space provided between said first and second mentioned members in such a manner as to cause the outwardly moving steam to bubble therethrough to heat and deaerate the water.

6. Apparatus for heating and deaerating water comprising a chamber for heating and partially deaerating contaminated water, a second chamber for completing the heating and deaeration, means for introducing contaminated water to be deaerated in broken-up form within the spacing of said first chamber, means for introducing deaerated steam into said second chamber, means

for directing partially contaminated steam from said second into said first chamber, mixer means within said second chamber operably associated with said water-directing means and said steam-introducing means, said mixer means having a pair of upwardly projecting cup-like portions, means for holding said cup-like portions in a spaced-apart relationship with respect to each other to provide a steam space therebetween and

10 for directing steam from said steam space upwardly and outwardly into the spacing of said second chamber, one of said cup-like portions being adapted to receive water from said directing means and to direct the water under low loads 15 towards the spacing between said cup-like members and under normal and higher loads towards the outwardly-projected steam in such a manner as to complete the heating and deaeration of the water.

7. Apparatus for heating and deaerating water comprising a chamber for heating and partially deaerating contaminated water, a second chamber for completing the heating and deaeration, means for introducing contaminated water to be deaerated in broken-up form within the spacing of said first chamber, means for introducing deaerating steam into said second chamber, means for directing partially contaminated steam from said second into said first chamber, means for 20 directing partially heated and deaerated water from said first chamber into said second chamber, mixer means, said mixer means having an upwardly sloped surface portion for receiving water from said directing means, said mixer means having a second upwardly sloped surface portion operably disposed in a spaced-apart relationship with respect to said first-mentioned portion in such a manner as to provide a steam chamber therewith, the steam chamber of said 25 mixer means being connected to said steam-introducing means, and means directing steam outwardly into the spacing of said second chamber in sheet form from said steam chamber, a valve seat extending from one of said surface portions 30 to the other within the steam chamber, and means operably associated with said seat for varying the supply of steam in accordance with load conditions, said first-mentioned surface portion directing the water over its surface and into 35 heating and deaerating relationship with respect to the steam sheet.

8. Apparatus for heating and deaerating water comprising a chamber for heating and partially deaerating contaminated water, a second chamber for completing the heating and deaeration, means for introducing contaminated water to be deaerated in broken-up form within the spacing of said first chamber, means for introducing deaerated steam into said second chamber, means 40 for directing partially contaminated steam from said second into said first chamber, means for directing water from first chamber into said second chamber, mixer means operably associated with said steam-introducing means and said water-directing means, said mixer means having a portion for collecting the water introduced within said second chamber by said directing means, said mixer means having a second portion operably associated with said first-mentioned portion and providing a steam space therewith, an annular valve seat extending about said steam space, radial portions extending outwardly along the spacing between said portions from said valve seat, and means for directing steam along said steam space past said valve seat and radially-out-

wardly in sheet-like form between said radial portions and into the spacing of said second chamber, said first-mentioned portion directing the water into heating and deaerating contact with the steam moving outwardly from the valve seat.

9. Apparatus for heating and deaerating water comprising a heating and deaerating chamber, means for introducing contaminated water to be deaerated within the spacing of said chamber, and valve means for introducing deaerating steam into said chamber and into heating and deaerating contact with the contaminated water, said chamber having a water-collecting portion, and means extending from said valve means into the water-collecting portion of said chamber for damping said valve means.

10. Apparatus for heating and deaerating water comprising a chamber for heating and partially deaerating contaminated water, a second chamber for completing the heating and deaeration, means for introducing contaminated water to be deaerated within the spacing of said first chamber, means for introducing deaerating steam into said second chamber, means connecting said first and second chambers for introducing partially contaminated steam from said second chamber into said first chamber to effect a preliminary heating and deaeration of the water being introduced into said first chamber, means for directing partially heated and deaerated water from said first chamber into said second chamber, and means associated with said water-directing means and said steam-introducing means and having valve portions for directing the steam into heating and deaerating contact with the water within said second chamber, and an extending vane-like damper portion operably associated with at least one of said valve portions.

11. Apparatus for deaerating water comprising a chamber for heating and partially deaerating water and a second chamber for completing the heating and deaeration, means for introducing contaminated water to be deaerated into said first chamber, means for introducing deaerating steam into said second chamber, means connecting said first and second chambers for introducing partially contaminated steam from said second chamber into said first chamber to effect a preliminary heating and deaeration of the water being introduced into said first chamber, means shaped to guide partially heated and deaerated water from said first chamber into said second chamber, and mixer means operably associated with said water-guiding means and said steam-introducing means and having a pair of operatively associated portions, one of said portions being shaped to direct steam from said steam introducing means substantially radially-outwardly into space provided by said second chamber, the other of said portions being shaped to direct water from said water-guiding means substantially radially-outwardly along a heat-receiving and somewhat parallel path with respect to the outwardly directed steam, and then, into convergence with such steam within the space of said second chamber beyond said mixer means.

12. Apparatus for deaerating water comprising a chamber for heating and partially deaerating water and a second chamber for completing the heating and deaeration, means for introducing contaminated water to be deaerated into said first chamber, means for introducing deaerating steam into said second chamber, means connecting said first and second chambers for introducing partially contaminated steam from

said second chamber into said first chamber to effect a preliminary heating and deaeration of the water being introduced into said first chamber, mixer means having means operably associated with said steam-introducing means and being shaped to direct the steam under suitable acceleration therealong and substantially radially-outwardly therefrom in sheet-like form into space provided by said second chamber, said mixer means also having means shaped to guide partially heated and deaerated water from said first chamber into said second chamber and directing it under acceleration substantially radially-outwardly therefrom along the sheet-like steam in a heat exchange relation therewith within the space of said chamber.

13. Apparatus for heating and deaerating water comprising a chamber for heating and partially deaerating contaminated water, a second chamber for completing the heating and deaeration, means for introducing contaminated water to be deaerated in broken-up form within the spacing of said first chamber, means for introducing deaerating steam into said second chamber, means for directing partially heated and deaerated water from said first chamber downwardly under acceleration into said second chamber, mixer means operably associated with said steam-introducing means and with said water-directing means, said mixer means having a pair of operably associated wall portions, one of said wall portions being shaped to direct the steam being introduced upwardly and outwardly within the spacing of said second chamber, the other of said wall portions being shaped to direct the accelerated water outwardly and upwardly within the spacing of said second chamber above and along the outwardly directed steam, and then, when water-acceleration is lost into convergence with such steam within the spacing of said second chamber.

14. Apparatus for heating and deaerating water comprising a chamber for heating and partially deaerating contaminated water and a second chamber for completing the heating and deaeration, means operably connecting said first and second chambers, means for introducing contaminated water to be deaerated into said first chamber, means for introducing deaerating steam into said second chamber, said connecting means being arranged to direct partially contaminated steam from said second chamber into said first chamber, means for directing partially heated and deaerated water from said first chamber into said second chamber, mixer means operably associated with said connecting means and with said water-directing means, said mixer means having a pair of sloped wall portions, one of said portions being positioned above the other portion, said portions being operably associated with each other and providing a steam chamber, the upper of said portions being sloped-upwardly to direct partially heated and deaerated water therealong and in circular sheet form upwardly under acceleration therefrom within the spacing of said second chamber, the lower of said portions being sloped-upwardly to direct steam from the steam chamber therealong and in circular sheet form upwardly therefrom and within the spacing of said second chamber along and beneath the water sheet in such a manner that the water and steam sheets will initially flow parallel in a heat exchange relation with each other and that the water sheet will then fall upon the steam sheet beyond said mixer means.

15. Apparatus for heating and deaerating water comprising a chamber for heating and partially deaerating contaminated water, a second chamber for completing the heating and deaeration, means for introducing contaminated water to be deaerated in broken-up form within the spacing of said first chamber, means for introducing deaerating steam into said second chamber, means for directing partially contaminated steam from said second into said first chamber, means for directing partially heated and deaerated water from said first chamber under gravity acceleration downwardly into said second chamber, mixer means operably associated with said steam-introducing means and with said water directing means and having portions constructed and arranged to project the steam upwardly and outwardly therefrom and within the spacing of said second-mentioned chamber in sheet-like form, said mixer means having a portion constructed and arranged to direct the downwardly-introduced and accelerated water outwardly and upwardly therefrom in sheet-like form into the spacing of said second chamber and into heating and deaerating contact with the steam sheet within such spacing.

16. Apparatus for heating and deaerating water comprising a chamber for heating and partially deaerating contaminated water, a second chamber for completing the heating and deaeration, means for introducing contaminated water to be deaerated in broken-up form within the spacing of said first chamber, means for introducing deaerating steam into said second chamber, means shaped to direct water that is partially heated and deaerated in said first chamber downwardly under gravity acceleration into said second chamber, said water-directing

means being associated with said steam-introducing means, and mixer means having portions providing a steam passage and being constructed and arranged to direct the water and steam therefrom to enter spacing of said second chamber in substantially parallel-radially-outwardly-projecting heat-exchanging circular sheets under normal and high load conditions and being shaped to collect the water in said steam passage and to cause the steam to bubble through and scrub the collected water under low load conditions.

17. Apparatus for heating and deaerating water comprising a chamber for heating and partially deaerating contaminated water, a second chamber for completing the heating and deaeration, means for introducing contaminated water to be deaerated in broken-up form within the spacing of said first chamber, means for introducing deaerating steam into said second chamber, means for directing partially contaminated steam from said second into said first chamber, means for directing water that is partially heated and deaerated in said first chamber downwardly under gravity acceleration into said second chamber, said water-directing means being associated with said steam-introducing means, mixer means having portions constructed and arranged to direct the water and steam therefrom to enter spacing of said lower chamber in substantially parallel radially-outwardly-projecting heat-exchanging circular sheets under normal and high load conditions and being shaped to cause the steam to bubble through and scrub the water in said mixer means under low load conditions.

JOHN R. McDERMET.
